UNITED STATES PATENT OFFICE.

JOHN WIEST, OF YORK, PENNSYLVANIA.

HOIST.

SPECIFICATION forming part of Letters Patent No. 403,164, dated May 14, 1889.

Application filed September 19, 1887. Serial No. 250,097. (No model.)

To all whom it may concern:

Be it known that I, JOHN WIEST, a citizen of the United States, residing at York, in the county of York and State of Pennsylvania, 5 have invented certain new and useful Improvements in Hoists; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention has reference to hoists; and 15 it consists in the improved construction hereinafter explained, whereby a compact and efficient arrangement is presented and an easy and effective operation secured.

In the accompanying drawings, forming a 20 part of this specification, Figure 1 is a sectional elevation of a hoist embodying my improvements, the same being taken on the line $x-x$, Fig. 2, which figure is a plan view. Figs. 3, 3^a, and 4 are enlarged detail views.

25 A designates a suitable supporting-frame, which is preferably of rectangular formation, and is provided with a central cross-bar, A'. Mounted in bearings in the upper side bars of the frame are the ends of a power-shaft, B, 30 which is located adjacent to and parallel with one of the end bars of the frame, as shown in Fig. 2. This shaft B may be driven by any suitable means and imparts its rotation to a counter-shaft, E, through the medium of a 35 worm, C, on said shaft B and a worm-wheel, D, on the shaft E.

In the present case the prime motor is an 40 electric motor, and the electricity for driving the same may be obtained from the electric light or power mains of a city service, or from any other source, and in cases where it is desired to use a portable electric hoist remote from any electric mains—as, for example, in the hoisting of building material or the raising of stone, &c., from wells, shafts, quarries, and all the various uses to which a hoist is applicable—a storage-battery is provided for operating the same.

In the case of the use of electricity as the 45 motive power the power-shaft B serves also as the armature-shaft of the motor, as shown; but I do not limit myself to the use of this hoist

with an electric motor, for any other power may be employed for driving the power-shaft; nor does the construction of the frame or the 55 arrangement of the hoisting mechanism thereon constitute any part of my invention. It can be changed or varied and the hoist made fixed or portable, according to the purpose for which it is to be used.

60 One end of the counter-shaft E is provided with a ball-head, e, designed to rest in a correspondingly-shaped recess, e', in the upper end of a bracket, e², secured to frame A adjacent the worm-gearing. A universal bearing 65 is thus secured, so as to permit the limited lateral movement of shaft E. The shaft E near its other end is supported by a journal box or bearing, e⁴, secured to cross-bar A' by bolts e⁵ e⁶, passed through slotted ends of said 70 box, whereby the same is capable of being moved with shaft E.

By reference to Fig. 2 it will be seen that a portion of said shaft E extends beyond said box or bearing e⁴ for the attachment of a friction-pulley, H. In the rear end bar and the cross-bar A' of the frame bear the ends of the windlass-shaft I, upon which is mounted the windlass J, provided with the usual flanges, J'. Upon the shaft I, between the windlass 80 and the bar A', is mounted a hollow friction-wheel, which has on the interior surface of its rim a friction-surface and carries at its center a small friction-pulley, L. To a stud or projection, a, secured to the cross-bar A', is 85 fulcrumed a lever, b, the lower end of which is secured to the journal box or bearing e⁴ by a screw or bolt, e⁶, so as to effect the sliding thereof in the desired direction.

From the foregoing it will be seen that as 90 the lever b is moved to the left, Fig. 1, the friction-wheel H will be moved in contact with the interior surface of the rim of the wheel K, so as to rotate the windlass and raise the load to be elevated. By moving the lever in an opposite direction to the right the pulley H will be 95 forced against the pulley L, so that the latter will be revolved to turn the windlass in a reverse direction and at a greater degree of speed. The necessity for this will be understood that in raising loads in many cases it is desirable to lower the rope after the latter has been discharged at a much faster speed than what was required in raising the load.

The movement of the lever may be effected by hand, treadle-power, or otherwise.

In the drawings I have represented a pair of electro-magnets, *c*, on each side of the lever, which are designed to be alternately positively and negatively energized in order to secure the attraction and repulsion of the lever.

The circuit-wires *c'* of the magnets *c* may run to any point near or remote from which it is desired to operate the hoist, and by means of a switch or switches introduced into this circuit at one or more places the hoist may be there controlled in a manner that will be readily understood. For example, if the hoist is being used for raising grain or merchandise to the different floors of a warehouse, the circuit-wires *c'* will run successively to each floor, and by means of a switch located on each floor the hoist can be started or reversed at any one of the landings.

I provide an improved brake for my hoist, which brake consists, as shown in Fig. 1, of a strap, *d*, which is connected to the frame at one side and extends around the pulley *K*, and is connected by a link, *e*, with one end of a bell-crank, *f*, pivoted in the frame and having its other end connected by a rod, *g*, with foot-pedal at the bottom of the frame. By depressing the pedal the strap is caused to bear against the periphery of the wheel and cause its stoppage.

I claim—

1. In a hoisting apparatus, the combination,

with the power-shaft having a worm-gearing, of the counter-shaft provided with a worm-wheel and having a universal bearing at one end and carrying a friction-pulley at the other end, the slotted journal-box, the lever connected thereto, and the windlass having a friction-pulley, substantially as set forth. 35 40

2. The combination of the shaft *E*, having one end provided with a universal bearing, a windlass-shaft and windlass, a hollow friction-pulley and its smaller pulley located on said windlass-shaft, a pulley located on the shaft *E*, and electro-magnets for moving said shaft *E* against the interior of said hollow pulley or its smaller pulley, substantially as and for the purpose set forth. 45

3. The combination of the power-shaft *B* 50 and counter-shaft *E*, and worm-gearing between the same, a universal bearing and a transversely-movable bearing for said shaft *E*, pulley on the latter, a windlass-shaft having hollow friction-pulley and smaller friction-pulley, and a lever for moving said transversely-movable bearing, substantially as and for the purpose set forth. 55

In testimony whereof I affix my signature in presence of two witnesses.

JOHN WIEST.
